UNITED STATES PATENT OFFICE.

SAM L. HEDRICK, OF WEWOKA, OKLAHOMA, ASSIGNOR, BY DIRECT AND MESNE ASSIGNMENTS, TO INTERNATIONAL PATENT CORPORATION OF AMERICA.

BAILER.

Application filed January 23, 1925. Serial No. 4,816.

To all whom it may concern:

Be it known that I, SAM L. HEDRICK, a citizen of the United States, residing at Wewoka, in the county of Seminole and State of Oklahoma, have invented new and useful Improvements in Bailers, of which the following is a specification.

This invention relates to improvements in bailers for wells and the like, the general object of the invention being to provide means for using the bailer to place water in a well, when desired, without interfering with its usual functions.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device.

Figure 2 is a view taken at right angles to Figure 1 and showing parts in section.

Figure 3 is an enlarged sectional view through the upper part of the device.

Figure 4 is a similar view but taken at right angles to Figure 3 and showing the parts in a different position.

Figure 5 is a section on line 5—5 of Figure 4.

In these views, 1 indicates the barrel of the bailer which is provided with a valve seat 2 at its lower end and a bail 2' at its upper end. A jar link 3 straddles the bail and is guided thereon by the bars 4 which are fastened to the bail, one on each side of the link. The upper ends of the two parts of the link are bolted to the socket member 5 to which the cable 6 is connected.

The lower end of the link is provided with a threaded socket 7 for receiving the threaded upper end of a sleeve 8 which has a second sleeve 9 connected thereto by the coupling 10. These two sleeves form a socket for receiving the upper end of the valve stem 11 of the valve 12 which engages the seat 2. This stem is formed of sections, as shown, and is connected with the valve by the swivel connection 13 and its upper end is provided with a head 14 which is

adapted to be engaged by a spring pressed dog 15 carried by a collar 16 rotatably mounted on the sleeve 8 and extending through a hole 17 in the sleeve. By rotating the collar 16 on the sleeve 8 the dog 15 can be moved away from the hole 17 so that it will not engage the head of the valve stem. The valve is provided with a T-shaped extension 12' which extends below the end of the barrel and is adapted to engage the bottom of the well, when the device is dropped in the well, and move the valve off its seat.

From the foregoing it will be seen that the device can be used in the usual manner to bail mud and water from a well, the jar link 3 acting to jar the barrel loose when stuck in the well. In this case the sleeve 16 is moved so that the dog 15 will not extend through the hole 17 so that the valve stem has free movement in the sleeves 8 and 9, the valve 12 closing when the barrel is lifted and being opened when the barrel is lowered by its extension 12' striking the bottom of the well. The blow of the link 3 on the bail 2 of the barrel will jar the device loose when stuck. When the device is to be used to place water in a well the collar 16 is turned so that the dog 15 will pass through the hole 17 and engage the head 14 of the valve stem. In this operation the device is lowered into the well with the barrel full of water and with the valve in closed position and after the barrel reaches the bottom of the well the link 3 is permitted to drop into the barrel and then to be pulled upwardly so as to cause the dog to engage the head of the valve stem which upon a further pull on the cable will lift the valve off its seat and thus discharge the water. The valve will remain off its seat as long as the link 3 is held in raised position.

Spiders 11' are arranged on the valve stem for guiding the same in the barrel.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A bailer of the class described comprising a barrel having a valve seat in its lower

2

end, a bail at its upper end, a double jar link straddling the bail, a cable engaging member connected with the upper end of the link, a valve for engaging the seat, a 5 valve stem, a socket member carried by the lower end of the link and receiving the upper end of the stem, a spring dog for connecting the socket member with the stem and means for holding the dog in an inactive 10 position.

2. A bailer of the class described comprising a barrel, a valve seat at the lower end thereof, a bail at the upper end thereof, a jar link straddling the bail, guide bars on

the bail for the link, a cable engaging member connected with the upper end of the link, a socket member connected with the lower end of the link and having a transverse hole therein, a rotatable sleeve on the socket member, a dog carried thereby and adapted to extend through the hole when the sleeve is in one position, a valve for engaging the seat, a valve stem having a head engaging the socket and adapted to be locked therein by the dog and an extension on the 25 valve extending below the barrel.

In testimony whereof I affix my signature.
SAM L. HEDRICK.
